UNITED STATES PATENT OFFICE.

DOMINICK RODGERS, OF PITTSBURGH, PENNSYLVANIA.

WRENCH.

Application filed August 30, 1922. Serial No. 585,203.

To all whom it may concern:

Be it known that I, DOMINICK RODGERS, a citizen of the United States of America, residing at Pittsburgh, in the county of 5 Allegheny and State of Pennsylvania, have invented certain new and useful Improvements in Wrenches, of which the following is a specification.

The present invention relates to wrenches 10 of the type which are provided with a slidably adjustable jaw, so that adjustments may be made instantly in order to quickly fit any particular sized nut on which the wrench may be operating. Several specific parts of 15 my invention are new, and the advantages of same will be further brought out in the specification as the description proceeds.

In the accompanying drawing forming part of the present specification, I have illustrated the nature of my invention, in the best mode I have so far devised.

Figure 1 is a side view of my invention; Fig. 2 is a cross-section taken on line 2—2 of Figure 1, and looking toward the right 25 as seen in Fig. 1;

Fig. 3 is a cross-section on line 3—3 of Fig. 1, looking toward the left;

Fig. 4 is a cross-section on line 4—4 of Fig. 1.

Fig. 5 is a perspective of a small spring used with my invention, and

Fig. 6 is a longitudinal section of a wrench commonly used.

In the drawings Fig. 1, gives a good view 35 of the wrench forming the present invention, in which 1 indicates a guide bar or stem, provided with a fixed jaw 2 on the one end thereof, and having also a pair of oppositely disposed longitudinal grooves 3 and 4 formed 40 therein. The grooves 3 and 4 preferably extend from a point 5 to the outer end 6 of the guide-bar 1, for a purpose which will be described.

Slidably mounted on the guide-bar 1 is the 45 slidable jaw 7, the shape of which is illustrated in Figures 1 and 3 of the drawings. The lower portions of the fixed and slidable jaws are cut away at 8 and 9 respectively to form "finger-grips", for the purpose of advancing the slidable jaw into intimate contact with an article such as the nut 10, before adjusting the locking traveler or wedge 50 11 into locked position.

The locking traveler 11 is of the form 55 shown in Figures 1 and 2 of the drawings, having a pair of oppositely disposed lips

12, 13 adapted to slidably operate in the grooves or channels 3 and 4. The traveler 11 also has an inclined or wedged surface 14 adapted to engage the complementary inclined socket 15 formed in the slidable jaw 7, and a portion of the sides of the traveler at 16, 16 are cut away in order to conveniently enter the socket 15 as is readily understood. A thumb-hold 17 is also provided in the locking traveler 11 as shown for advancing the same into position against the sliding jaw 7.

In order to mount the traveler 11 on the guide-bar 1, and hold it securely on the said bar 1, I have provided two convenient means of accomplishing the purpose desired. One means comprises the pair of small parts or blocks of metal which fit into the grooves 3 and 4, which are designated 18, 18, and said blocks or fillers are secured in position by means of two small countersunk screws 19, 19 as illustrated clearly in Figures 1 and 4 of the drawings. The second means consists of a pair small springs 20, shown in Figure 5. It is evident that both means may be used on the same wrench, in which case the springs 20 merely function as a convenient resilient buffer for the locking traveler and slidable jaw. However in some cases it may be advisable in order to cheapen the cost of manufacture, and simplify the construction to merely use the pair of springs 20, and omit the blocks 18, 18 entirely, in which case the springs form all 90 the abutments necessary to hold the traveler 11 and jaw 7 on the guide-bar 1.

In many wrenches of the general type under consideration one side or the other of the bar 28 is formed into teeth, say on the 95 face 21, or 22, the function of the wedge 25 used being in such cases to merely secure the teeth of the slidable jaw 23 as illustrated in Figure 6 into the teeth 24, the latter of course taking all the load strain of the slidable jaw 23.

In my invention I have gained an advantage by eliminating the cost of manufacturing teeth, with quicker slidable operation of the jaw 7 and traveler 11, as there are no 105 teeth on the bar 1 nor the slidable jaw 7 to get engaged with each other at points other than the desired point of engagement. In my type of wrench it is seen that when the slidable jaw 7 is brought up against the nut 110 10, and the follower or locking traveler 11 adjusted in proper position so that the bev-

eled surface 14 engages the socket 15, and the guide-bar is rotated in a clock-wise direction or downward as seen in Fig. 1, about the center of the nut as a center of rotation, 5 that the slidable jaw socket 15 impinges against the inclined surface of the wedge 11 at point 26; and also the said slidable jaw impinges at point 27 on the upper edge or back of the guide-bar 1. As no movement 10 longitudinally of the jaw 7 can take place due to the wedging action of the wedged traveler 11 it is evident that the wrench has securely gripped the nut 10. From which it is at once seen that I have provided a wrench 15 which is just as serviceable from a mechanical standpoint as the toothed guide-bar type, and with the added advantages of being more quickly adjusted in working position, and with cost of manufacture lessened. 20 Moreover the details of construction such as the two types of means suggested and shown for the holding of the traveler 11 on the guide-bar 1, are a further advantage.

I claim:

25 1. In a wrench, a guide-bar having a fixed jaw, and a pair of opposed longitudinal grooves formed in the sides of the guide-bar, a slidable jaw mounted on and enclosing

the guide-bar, a beveled socket in the slideable jaw, a wedge-shaped traveler adapted to 30 contactingly engage the beveled socket of the slideable jaw and the guide-bar, to provide by a wedging action a locking means for limiting the travel of the slideable jaw in a direction which would release the grip 35 of said jaws of the wrench on an object being held therebetween, a pair of inwardly-turned lips formed on the traveler in engagement with the guide-bar grooves, and resilient means for securing said traveler 40 and slideable jaw on the guide-bar.

2. In a wrench, a guide-bar having a pair of longitudinal side-grooves and a fixed jaw, a slideable jaw having a wedge-shaped socket therein and mounted on the guide-bar, a complementary wedge-shaped traveler having a pair of inwardly-turned lips engaging the guide-bar grooves, means forming a resilient stop for the traveler located in the guide-grooves, and independent means 50 for securing the traveler and resilient stopping means on the guide-bar.

In testimony whereof I affix my signature.

DOMINICK RODGERS.
